UNITED STATES PATENT OFFICE.

ANDREW CAMPBELL, OF NEWARK, NEW JERSEY.

MACHINE FOR FEEDING PAPER TO PRINTING-PRESSES.

Specification of Letters Patent No. 13,333, dated July 24, 1855.

To all whom it may concern:

Be it known that I, ANDREW CAMPBELL, of Newark, in the State of New Jersey, have invented certain new and useful improvements in the machine for feeding sheets of paper to printing-presses and for other purposes and delivering and piling the same, of which the following is a full, clear, and exact description, reference being had to the accompanying drawings, making part of this specification, in which—

Figure 1, is a front elevation; Fig. 2, a side elevation; Fig. 3, a longitudinal vertical section; Fig. 4, a separate view of one of the endless cam grooves for guiding and operating the grippers; Fig. 5, a separate view of the other cam groove; Fig. 6, a cross section of part of Fig. 4; Fig. 7, sections of the wheels for guiding the endless band or chain that carries the grippers; Fig. 8, a separate elevation of the sheet lifting apparatus; Fig. 9, a plan of the same; and Figs. 10, and 11, cross sections of the same taken at the lines A, a, and B, b, of Fig. 8. Fig. 12, is a plan of one of the grippers and part of the band or chain; Fig. 13, separate views of one of the wheels for guiding the band or chain representing the parts for reversing the grippers; Fig. 14, an elevation of part of the frame showing the valve seats for the rotary valve leading to the blowing and the exhausting bellows; and Fig. 15, is a vertical section taken at the line C, c, of Fig. 14. Fig. 16 is a section of the rotary valve wheel taken in a plane parallel with its face; and Fig. 17, a cross section thereof taken at the line D, d, of Fig. 16.

The same letters indicate like parts in all the figures.

The purpose of my said invention is to take sheets of paper, one by one, from a pile and feed or carry them to a printing press, or to any other machine, designed to perform some operation upon them and then to carry them off and deliver them on a pile accurately, one of the chief designs in delivering them being that they may be transferred to the place from whence they are fed that they may register accurately as when sheets are to be printed on the reversed side. And in the accompanying drawings I have represented my said invention as applied to a cylinder printing press, representing simply the cylinder of such a press, the other parts being familiar to constructors of printing presses.

In the accompanying drawings *a*, represents a suitable frame, and *b*, a table on which a pile of sheets of paper *c*, is placed. The pile of sheets of paper is put on a board *d*, of the required size and the board is placed on the table *b*. This table is secured to a cross head *e*, the ends of which are attached to two vertical rods *f*, *f*, adapted to slide accurately in the frame. And at the lower end these rods are provided with cogged racks *g*, *g*, one for each rod, the cogs of which engage pinions *h*, *h*, one on each end of a horizontal shaft *i*, carrying a crank handle by which the attendant lets down the table to its lowest position to receive the board with the pile of sheets of paper. At the ends of the table there are two vertical guide plates *k*, and *l*, one at each end, the one *k*, being fixed, and the other *l*, hinged at its lower edge so that it can be let down to admit of putting on the pile of sheets, and then thrown up in a vertical position and held in place by a spring catch *m*. There are end plates *n*, *n*, on each end of these guide plates attached by screw bolts passing through slots for adjusting their distance apart, and these end plates embrace the sides of the pile and thus guide the pile laterally while the end plates guide the ends of the pile. The size of the table should be suited to the size of the sheets constituting the pile, and when the size of the sheets is to be changed the table is to be changed also, the back plate, that is the one not hinged, as well as the end guide plates can be shifted to suit the size of sheets.

The table with the pile of sheets is forced up by the attendant until the top of the pile is brought in contact with a gage and holding bar *o*, which extends across the pile and which is attached to two arms *p*, *p*, on a free rock shaft *q*. The bar makes pressure on the pile by its weight, aided, if desired, by a spring. When the pile is lifted it is held up by the friction of a pad acted upon by a spring *r*, attached to the frame, the pad having a stem which passes through the frame to receive the tension of the spring to make pressure on the face of the ratchet wheel *s*, on the shaft *i*. This ratchet wheel is for the purpose of lifting the table with the pile as it is reduced, to keep the top of the pile always at the same elevation. The periphery of the wheel *s*, is armed with fine ratchet teeth and acted upon by a series of feed hands or pawls *t*, jointed to a feed lever

u. And I employ a series of these feed hands and make them of different lengths to insure accuracy of feed without the necessity of making the ratchet teeth so fine as to 5 be deficient in strength.

The feeding lever u, is attached to a hub v, that turns freely on the shaft i, and provided with a counter weight w, sufficient to lift up the feed with its feed 10 hands or pawls. And to the feed lever is jointed a gage rod x, working in suitable guides, and with the upper end extending up to the point of a set screw y, on the end of the gage and holding bar, so that 15 the weight of the gage bar overcomes the force of the counter weight w, and forces back the feed lever whenever the pile of paper permits the gage bar to descend sufficiently to require the feed motion to take 20 place. When the feed lever has been forced back by the gage bar it is then acted upon to turn the ratchet wheel and lift the pile, by a cam z, on a shaft a', which makes one 25 complete revolution for every operation of the machine. This operation must be delicate, as the sheets are necessarily thin and it is important that the top of the pile should be always at the same level, and for that reason the axis of the joint of the gage rod 30 x, with the feed lever is at the same distance from the axis of the shaft i, on which the feed lever turns, as the pitch of the pinions h, h, on this shaft, which lift the table. In this way the gage rod becomes the exact 35 gage of the lifting of, or the necessity for, lifting the pile.

At the time of removing each sheet from the pile the holding and gage bar must be lifted from the pile to permit the grippers 40 (to be hereafter described) with the sheet to pass under it, and this is done by a cam b', on a shaft c', which makes one revolution for every complete operation of the machine. This cam acts on a roller or wrist projecting 45 from one of the arms of the gage bar.

The sheets are taken from the pile one by one and instead of drawing or sliding them off from the pile they are lifted by one end and rolled off. The top sheet is taken up 50 by the action of an exhausting bar d', which is hollow and perforated with numerous small holes through that face of it which operates on the surface of the sheet. This bar is hung by hollow journals at each end 55 to two hollow arms e', e', of a hollow shaft f', mounted in suitable boxes in the frame, the journal of this rock shaft at one end is solid, and at the other hollow, and communicates with the seat of a rotating valve 60 wheel g', on the outside of the frame. The exhausting bar is brought down onto the surface of the top sheet and overlaps the edge. The required motion to bring down 65 the bar is imparted by the rocking motion of the rock shaft which is provided with a

crank arm h', outside the frame operated by a connecting rod i', the outer end of which is bifurcated (as represented by dotted lines in Fig. 2) to embrace and slide on the cam shaft c', which carries a cam j', that 70 acts on a roller or wrist k', on the connecting rod, the said rock shaft being turned in the opposite direction by the tension of a helical spring l', surrounding it and attached at one end to the frame and at the other to a 75 collar m'. The tension of this spring also forces the rock shaft endwise to keep its hollow end in close contact with the surface of the port leading to the rotating valve g'. After the bar has been brought down onto 80 the sheet it is then turned to bring its perforated surface in proximity with the surface of the sheet, and this is done by having it turn on its axis as the rock shaft completes its motion. The end of the exhaust 85 bar has a pinion n', the cogs of which engage the cogs of a sector rack o', on another arm p', that turns on the rock shaft and which is connected with it by a helical spring q', so that this rock arm moves with 90 the arms e, e, attached to the rock shaft as they bring down the exhaust bar; and so soon as the end of the sector rack strikes against a stop r', the sector rack and its arm are stopped while the rock shaft continues 95 to be moved by the cam j', and hence the exhaust bar is caused to turn as it continues to be moved, by the engagement of its pinion n', with the sector rack. This gives it a rolling motion which effectually keeps its 100 rear edge in contact with the surface of the sheet, and its perforated surface nearly in contact with the surface of the sheet, the edge of the bar overlapping the edge of the sheet. Just as this takes place the exhaustion 105 is brought into action. There is an exhausting bellows s', the bottom flap of which is weighted to exhaust by its descent and it is connected by two rods t', t', with two arms u', u', of a sleeve shaft v', fitted to a 110 rock shaft w', which receives motion from a grooved cam x', on the shaft a', that acts on a connecting rod y', that takes hold of a crank z', on the end of the rock shaft. And this rock shaft has a pin a², projecting from 115 it which passes through a slot in the sleeve shaft of such length in the direction of the circumference that when the bottom flap of the bellows has been lifted the rock shaft can make its return positive motion leaving 120 the flap of the bellows to descend by gravity. In this way I avoid all the inconveniences which would arise if the flap of the bellows had a positive motion which would of necessity require the motions to correspond with 125 the movements of the machine or the operations to be performed by the exhaust.

The upper part of the bellows communicates by a tube b² with a port c² (see Fig. 14) the direction being partly represented by 130

dotted lines. And this port opens through a valve seat d^2 , making part of the frame and specially represented in Fig. 14. To this valve seat is fitted the face of a rotary valve 5 g^1 represented separately in Figs. 16 and 17. And the port of the valve seat communicates with a corresponding port c^2 in the valve which by an internal channel communicates with a long aperture f^2 near the periphery 10 which corresponds in position with a port g^2 in the valve seat leading to the hollow rock shaft which carries the exhaust bar. In this way it will be seen that so long as the port f^2 of the valve is in communication 15 with the port g^2 in the valve seat the exhaust bar will be exhausted. The periods of opening and closing this communication are governed by the turning of the valve which makes one revolution for each complete operation of the machine, which motion is imparted by a pinion h^2 on a shaft i^2 which engages cogs on the periphery of the valve that turns on a center pin j^2 .

The surface of the exhaust bar is not flat, 20 but of the form represented in the sections Figs. 3 and 10, which form is nearly cylindrical back of the series of perforations so as to roll on the pile and slightly running beyond or out of the circle as it approaches 25 the series of perforations to make pressure on the pile within the edges of the sheets and thus cause the edges of the pile to open fan like (as represented at Fig. 10). The perforated surface is curved inward and 30 then extends forward to overlap the edge of the pile. The object of thus hollowing the perforated surface is that the top sheet which is drawn to the surface by the force 35 of the exhaust may be curved inward while 40 the other sheets, not so held, but which have a tendency to follow the top sheet by contact of surfaces, may be separated by their tendency to remain straight or in the line of the chord.

45 By reason of the curved surface of the exhaust bar and the fact that its perforated surface is not brought into direct and absolute contact with the top sheet, the moment the exhausting action takes place a current 50 of air is induced inward which strikes across the edges of the several sheets and thus tends to separate them while it carries the top sheet to the perforated surface where it is held by the pressure of the air. And 55 to insure the separation of the top sheet from the pile, the moment the exhausting action above named has taken place two currents of air are forced across—that is, along the line of the exhaust bar and between the 60 top sheet then held to the surface of the exhaust bar and the other sheets. This is effected by two blow pipes k^2 k^2 , one at each end of the exhaust bar and blowing toward each other. These two blow pipes project 65 from a hollow rock shaft l^2 , one end of

which communicates with a port m^2 in the valve seat d^2 and the other carries a sector pinion n^2 engaged by a rack o^2 on the end of a sliding rod p^2 operated by a cam q^2 on the cam shaft, the form of which cam is suited 70 to give the required motions to carry the ends of the blow pipes to the required position for separating the sheets and to permit them to be carried back by the tension of a helical spring r^2 on the rock shaft, which 75 spring also tends to force the said shaft toward its port in the valve seat. This port communicates with a port s^2 in the valve and this port by a suitable channel way t^2 passes out through the front face of the 80 valve at u^2 , where it communicates by a bent pipe v^2 with a channel way w^2 in the frame leading to the bottom of a blowing bellows x^2 . The top flap of this bellows is operated in the same manner as the bottom flap of the 85 exhaust bellows and therefore not necessary to be described.

The moment the exhausting action begins to take place the exhaust bar rolls back a little with the sheet on it, which is done by 90 a slight depression y^2 in the surface of the cam; and the blowing through the blow pipes to separate the sheets does not take place until the exhaust bar has reached the position just designated, as represented in 95 Fig. 3. The exhausting bar then makes another slight movement backward, the blow pipes following it. This is to give sufficient space for the movement of what I denominate the transferring and holding bar. And 100 so soon as the pile has been effectually separated from the top sheet, and the holding bar has advanced, the blow pipes are drawn back out of the way by the tension of the spring, the cam being so formed as to permit this back motion. In addition to the two blow pipes already described, I contemplate using two or more blow pipes z^2 that 105 radiate from the same hollow rock shaft to aid in effecting the separation. 110

The transferring or holding bar a^3 , is hollow and connected by hollow arms b^3 , with a hollow shaft c^3 , which is made like the other two hollow shafts before described, and communicates with a port d^3 , in the 115 valve seat d^2 . And the valve g^1 , has two ports e^3 , f^3 , which alternately communicate with the port d^3 . One of these ports, e^3 , communicates by the channel b^2 , with the exhausting bellows, and the other f^3 , with the 120 blowing bellows. The lower edge of this bar is slightly rounded to press on the pile, after the separation has taken place, which motion is imparted by a cam g^3 , on the shaft a^3 , which acts on a connecting rod that takes 125 hold of a crank h^3 , on the end of the hollow shaft c^3 , the back motion for lifting being effected by a helical spring i^3 , on the shaft. The moment this transferring or holding bar is brought down on the pile the port e^3 , 130

in the valve has reached the required position to effect a communication with the exhausting bellows. The front face of the bar, facing the exhausting bar, is pierced 5 with numerous small holes j^3 , like the exhaust bar, through which a current is induced. Now as the exhaust begins to operate in this holding bar the exhaust bar rolls forward to carry the top sheet, which 10 it holds, toward the perforated surface of the transferring or holding bar, and at this time another port k^3 , in the valve which communicates with the blowing bellows is brought in communication with the port 15 leading to the exhaust bar thus inducing a forced current through the apertures of the exhaust bar at the same time that an exhaust current is induced through the apertures of the holding bar, by means of which 20 the sheet is transferred from the exhaust to the holding bar there to be held by the force of the exhaust until it is gripped by the grippers (to be presently described) and the valve cuts off the communication be- 25 tween the holding bar and the exhaust bellows and opens the communication with the blowing bellows to liberate the sheet as the grippers take and carry it away; and then the form of the cam g^3 , is such as to permit 30 the holding bar to be lifted from the pile preparatory to the next operation, but it is held there until just before the exhaust bar begins its next series of evolutions. Immediately in front of the pile there is a 35 small shaft l^3 , which carries a series of springs m^3 , (four more or less). These springs are attached to the shaft, are coiled around it, and their ends project in tangent lines. One end of the shaft has a pinion n^3 , 40 (see Fig. 2), which turns freely but which is connected with a spring clutch box o^3 , so that the pinion can be turned in one direction without imparting motion to the shaft, but when turned in the opposite direction 45 the shaft is clutched and turned by it. The pinion is engaged by a sector rack p^3 , on the hollow shaft of the exhausting and blowing holder, so that the rocking motion of this shaft imparts the required motions 50 to the shaft and its springs. The ends of these springs lie under the edge of the pile, and when the shaft is turned they first lift the edge of the pile slightly, and then slip across the edges of the sheets constituting 55 the pile to separate them just as piles of sheets of paper are separated by flipping the thumb across them, called thumbing a pile.

The edge of the sheet being held as described it is gripped by three grippers q^3 , 60 (the number may be more or less) attached to, and carried by two endless chains or bands r^3 , of peculiar construction and passing around two wheels s^3 , see Fig. 2, at each end of the cylinder t^3 , of a printing press 65 receiving motion from some suitable motor

thence pass up over two guide wheels u^3 , on a free shaft at the back and near the top of the frame, then around two guide wheels v^3 , on the shaft i^2 , at the front end of the frame, the said shaft thus receiving motion 70 from the chains or bands; then back over two guide wheels w^3 , on a tubular shaft that runs freely on the shaft a' , before described, and then down under the wheels on the cylinder of the printing machine. Each chain 75 or band is composed of two cords, each of one or more strands of cat gut, or equivalent therefor, wrapped around with metallic wire like the base strings of piano forte, by means of which I obtain the required 80 strength, durability, and flexibility. The two cords thus prepared are passed through holes in a series of metallic cross pieces x^3 , secured at equal distances apart to constitute cogs, which enter corresponding recesses in the series of wheels to obtain accuracy of movements in all the parts. The cross pieces or cogs x^3 , are secured on the cords by making the holes just large enough 85 to receive the cords; these holes are then 90 tapped and when the cogs are in place they are hammered down to close onto the helical or thread like grooves formed by the metallic wrapping of the cords. The ends 95 of the cords are properly secured to the two 100 end cogs, and these two end cogs are connected by two links keyed together. In this way the two cords are held at equal distances apart. The cords are fitted to 105 grooves in the series of wheels around which they pass and as the cogs are fitted to recesses in the periphery of the wheels the same accuracy of position and movement is secured as in the case of cogged gearing. The two chains or bands are constructed in 110 like manner in every particular. Two sets of grippers are attached to these chains or bands and at equal distances apart, and the length of the chains is such that they make one entire evolution for two complete operations of the machine, so that there is one set of grippers for each complete operation. This is to secure a convenient length of 115 chain without losing motion or time in any portion of the operation, and therefore it will be apparent that the machine can be arranged with any number of sets of grippers from one upward.

The grippers are composed each of two jaws y^3 , and z^3 , one fixed and the other 120 hinged to open and close. The fixed jaws y^3 , are secured by their rear ends to a carrier rod a^4 , by being fitted to the rod by a feather or equivalent means so that they cannot turn on it. The movable jaws z^3 , are connected 125 with the fixed jaws by a hinge or knuckle joint b^4 , between the gripping part and the rod a^4 , to which the fixed jaws are attached, and the connection of the hinges is formed by another rod c^4 , parallel to the one holding 130

the fixed jaws, and the movable jaws are secured to this rod c^4 , by a temper screw, or other equivalent means, so that the turning of this rod will either open or close the jaws. 5 In this way it will be seen that the turning of one rod will shift the position of the jaws, and the turning of the other will open or close the jaws to grip or liberate the sheet of paper. The grippers are kept closed by 10 the tension of a helical spring d^4 , on the hinged rod c^4 , and attached at one end to the jaw, and at the other to the rod.

The carrier rod a^4 , of the fixed jaws is connected at each end to one of the chains by 15 a block of metal e^4 , secured to one of the cogs x^3 , and both ends of the rod project beyond the blocks and are provided with rollers f^4 , that run in guide grooves g^4 , and h^4 , one on each side and attached to the frame. The 20 form of the guide groove g^4 , on the right hand side is represented in the separate figures 4 and 6; and the form of the one on the left hand side is represented in the separate Fig. 5. As the rollers run in these grooves 25 the rod carrying the fixed jaws will be maintained in its proper elevation during its travel through the machine. At the bottom of the guide groove g^4 , on the right hand side there is another groove i^4 , of less width, 30 in which runs the crank pin j^4 , see Fig. 12, of a crank h^4 , on the carrier rod, and the form of this groove and the length of the crank determines the position of the gripping end of the jaws relatively to the carrying end. 35

When the grippers approach the position where they are to grip the edge of the top sheet (the position above described) they are gradually turned to present the jaws 40 downward in an inclined position to correspond with the edge of the sheet which inclines upward; and as the sheet is gripped the jaws are gradually turned back, or rather the carrying rod a^4 , moves faster than the 45 jaws to precede them. This is effected by the form of the guide grooves. The guide groove i^4 , in which the crank pin j^4 travels from the front circular end at l^4 , runs down at an inclination gradually depressing the 50 jaws, and at m^4 , it takes a direction more inclined downward, until it reaches a point, n^4 , and from this it runs up at a reversed inclination to the point o^4 , where it again assumes a direction parallel with the chain. 55 At the angle n^4 , there is a switch p^4 , hung on a fulcrum pin q^4 , and it is provided with a spring r^4 , the tension of which tends to keep it in the position represented in Fig. 4, and keeping the groove from m^4 , to n^4 , closed, 60 but as the crank pin strikes it it opens to permit the crank pin to pass and then closes behind the crank pin to compel it to pass up the opposite inclination. At the time the crank pin reaches the bottom of this groove 65 at n^4 , the carrying rod a^4 , continues to move

forward with the chains so that the crank pin becomes the axis on which the grippers are reversed or turned, and this axis is nearly in a line with the extreme end of the jaws, so that during this reversing motion of the 70 jaws their extreme end remains in a fixed position relatively to the sheet of paper, and to effect this the guide grooves in each side which guide the rollers on the carrying rod are curved upward in a segment of a circle 75 as at s^4 . During the operations just described the jaws of the grippers must be opened to receive, and then closed to grip, the sheet. This is effected by a crank t^4 , on the end of the hinge rod c^4 , which carries 80 the movable jaws of the grippers. The crank pin of this crank, as the grippers approach the sheet, strikes an inclined plane u^4 , which forces the jaws open by reason of the forward motion of the gripper carrier, 85 and as the grippers are reversed the crank pin gradually passes off the inclined plane to permit the jaws to be closed by the tension of the spring d^4 , on the hinge rod, and to ease off the closing, the crank arm slides 90 on a pin projecting from the side of the inclined plane and gradually leaves it. During these motions the inclined plane u^4 , is fixed, but as in this position it would be in 95 the way of other movements, it is attached to an arm v^4 , projecting from the hollow rock shaft c^3 , of the holder, before described.

The edge of the sheet having been gripped and the grippers recovered so that the jaws precede the carrier, the motion by the travel 100 of the chains gradually rolls off the sheet, and carries it off in the reversed direction of the position it occupied on the pile. To permit the passage of the grippers with the sheet, the holding gage bar o , is lifted from 105 the pile in the manner already described. The continued travel of the chains carries the sheet around the cylinder of the printing press, where it receives an impression and thence it is carried up in the rear end 110 over the shaft of the two guide wheels u^3 until the chains travel in a horizontal direction at top. The guide groove h^4 , on the left hand side is omitted at the places where the chains travel in curves. And the guide 115 groove g^4 , on the right hand side for the roller of the carrying rod a^4 , is also omitted, as the object of this groove on each side is simply to guide the carrier and chains during certain operations. But the groove i^4 , 120 for guiding the crank pin of the carrying rod is continued through the entire circuit to maintain the proper position of the grippers.

Above the feed table, already described, 125 there is another table w^4 , called the receiving table, mounted and operated in the same manner as the feeding table, by being attached to a cross head x^4 , attached at the ends to the two vertical rods y^4 , adapted 130

to work in slides, and provided with racks z^4 , at the lower end which engage pinion a^5 , on a shaft b^5 , parallel to the shaft i , for operating the feeding tables. The shaft is 5 provided with a ratchet wheel c^5 , and a ratchet lever d^5 , and hands e^5 , in every particular like the other except that it acts in the reversed direction to let down the table as the sheets are deposited on it, while the 10 feed table is gradually elevated as the sheets are removed.

The ratchet lever instead of having a counter weight like the other is provided with a direct weight f^5 , which tends to 15 bring the lever against a cam g^5 , on the shaft by which the ratchet motion is imparted, and which also tends to force up a gage rod h^5 , jointed to the ratchet lever at the same distance from the axis of the shaft 20 b^5 , as the pitch of the cogs on the pinions a^5 . This rod is guided by suitable slides, and its upper end is acted upon by an arm i^5 , on the end of the arbor j^5 , of a projecting wing or plate k^5 , which acts as a gage or holder. 25 This plate is forced down toward the surface of the receiving table, or rather the pile of paper deposited thereon, by the tension of a helical spring on its arbor, and lifted up at the required time by a rod l^5 , jointed 30 to an arm m^5 , the said rod being acted upon for this purpose by a cam n^5 , on the shaft a' . And the arbor j^5 , of the said gage plate is provided as above stated with another arm i^5 , which gages the upward motion of the 35 gage rod, so that when the receiving table is at a proper height the position of the arm i^5 , of the gage plate k^5 , prevents the gage rod h^5 , from rising, and holds up the ratchet lever d^5 . 40 The cam g^5 , on the shaft a' , has a depression, and when this depression passes, the ratchet lever d^5 cannot descend, and therefore the ratchet wheel is not acted upon, and hence the table is not moved. But when the 45 sheets accumulate and it becomes necessary to depress the table, the gage plate being held up by the pile, the arm i^5 permits the gage rods h^5 to rise, so that when the depression in the cam passes, the ratchet lever 50 falls back and the continued motion of the cam operates the ratchet lever and depresses the table. In this way it will be seen that the receiving table is kept at the required elevation during the operation of the machine, like the feed table, but simply reversed the one being gradually depressed as the other is elevated.

The gage and holding plate k^5 , as already stated, subserves also the purpose of holding down the rear edge of the sheets piled on the table, and the object of this is to prevent the rear edge of the top sheet of the pile from being disturbed and curled over so the next sheet is carried over to be 65 in turn deposited. As this plate is at the

back edge of the pile, and when depressed is in a horizontal position, it does not prevent the passage of the next sheet, and when that has been deposited, the plate is lifted by turning its arbor, the edge of the sheet 70 drops on the pile, and as the cam n^5 passes around, the plate is again depressed by its spring to make pressure on, and hold down, the edge of the sheet during the next operation. 75

The motions of the grippers with the sheet have been described, so far as carrying the sheet around the cylinder of the printing press, and up in the rear where the chains begin to travel forward in a horizontal direction, and it becomes necessary to describe the motions for carrying the sheet over, and dropping it on the receiving table. As the grippers are moved forward they pass over the holding plate k^5 , and over the 80 receiving table w^4 drawing the sheet after them; and when the sheet has reached the required position over the table the pin o^5 on the crank arm t^4 , on the rod of the movable jaws comes in contact with an inclined 85 plane p^5 , which turns the rod sufficiently to open the jaws and liberate the sheet. 90

Above the receiving table there is a packing plate q^5 , which is lifted to permit the grippers and sheet to pass under it, and 95 which is then let down to make pressure on the pile to pack down the pile and insure the laying of the sheets flat. This plate is connected by brackets r^5 , r^5 , with a cross head s^5 , provided at the ends with guide rods t^5 , 100 adapted to slide in appropriate boxes in the frame. This plate descends by gravity and is lifted by the arms u^5 , of a rock shaft v^5 , provided with another arm w^5 , acted upon by a cam groove x^5 , in the face of a wheel y^5 , which makes one revolution for each 105 complete operation of the machine. The arms u^5 , pass through slots z^5 , in the cross head, but these slots are of sufficient size to independently of the cross head and plate. To the back face of the cross head is fitted a bar a^5 , having slots through which the arms u^5 , of the rock shaft pass, and this bar is connected with the cross head by means 115 of screw bolts b^5 , that pass through slots in the bar, so that the arms of the rock shaft can impart a slight motion up or down to the bar independently of the cross head and plate. The object of this is to operate 120 punches c^5 , attached to the bar for the purpose of punching or burring the paper so that the pile can be moved without the danger of shifting the relative position of the sheets constituting the pile. From this it 125 will be seen that after the sheet has been deposited on the pile the arms of the rock shaft descend permitting the plate to descend by its weight to compact the pile, and then the continued downward motion of the 130

arms forces down the bar a^6 with its punches that pass through perforations in the plate and which are thus forced into the paper. And when the plate is to be lifted to permit 5 another sheet to pass under, the arms u^5 , are raised by the rock shaft which first lifts up the bar with its punches, and then the plate.

On the rear edge of the plate is mounted 10 a small arbor d^6 , which carries a series of springs e^6 , that extend under the plate; and this arbor also carries an arm f^6 , with a segment slot g^6 , to which is fitted the wrist pin of an arm h^6 , on the rock shaft v^5 , so that 15 as the plate is elevated and depressed by the rocking motion of the rock shaft, the wrist pin on the arm h^6 , moves up and down in the sector slot, which being of less radius than the arm carrying the wrist pin the 20 arbor is thus caused to vibrate so that in lifting the plate to permit the grippers to pass under, the springs are also lifted, and the moment the grippers have passed beyond the ends of these springs the rock shaft 25 begins to turn to let down the plate, and this first movement turns the arbor to bring the springs onto the sheet to make friction, so that the moment the jaws are opened the sheet is stopped while the grippers continue 30 their motion. This arrangement of springs is important to insure the deposit of the sheet in the proper place that all the sheets may be piled up regularly.

The bar a^6 , is provided with a series of 35 holes in its face (not shown in the drawings) that the stocks of the punches may be shifted to punch the holes in any part of the sheet. And the plate q^5 , is also pierced with numerous holes to prevent a sucking 40 action on the pile when the plate is lifted which would have a tendency to lift the sheets.

From the foregoing it will be seen that as 45 the sheets are taken from the feeding table and carried to the cylinder of the press they are reversed in leaving the pile and again turned over in passing around the cylinder of the press so that in passing up toward the receiving table the printed surface is 50 exposed to view that the work may be inspected, and as they are piled on the receiving table accurately, when the other surface of the sheets are to be printed it is only necessary to reverse the pile and transfer it 55 from the receiving to the feeding table, and they will be carried to the cylinder of the printing press and printed on the other face to correspond exactly with the printing on the first side, making what is termed a perfect 60 register.

After the grippers have deposited the sheet on the receiving table it is necessary that they should be reversed preparatory to taking the next sheet, because in gripping 65 the previous sheet they were turned and

therefore they must be brought back to their original position. This is effected in passing around the front guide wheels v^3 . The crank pin j^4 , of the gripper carrier continues to travel in the guide groove i^4 , which descends at an inclination from the point i^6 , to j^6 , see Fig. 4. and from j^6 , to l^4 , it runs in the segment of a circle, and from l^4 , to m^4 , it runs as before described in a reversed inclination to the place where the grippers are 70 turned. The position of this groove relatively to the guide wheel around which the chain passes is such that the crank arm k^4 , on the gripper carrier will be held inward toward the center as the carrier travels 75 around with the wheel.

As the gripper carried is moved forward it precedes the crank pin, and hence the jaws project backward, and in passing around from the top to the bottom of the guide 80 wheels it is necessary that the crank arm should continue back of the carrier so that in passing around the semi-circumference of the circle the grippers shall be reversed 85 relatively to the line of motion of the carrier, and thus have the jaws moving toward the edge of the sheet to be gripped. Now as the crank arm passes a horizontal plane (see Fig. 13) passing through the axis of the guide chain wheel and of the circular part 90 of the guide groove it is necessary that it should be forced downward, otherwise in passing that plane the carrier would begin to advance on the crank pin and finally precede it, and thus place the jaws so that they 95 would follow instead of preceding the carrier; but by forcing down the crank arm in passing that plane the crank and consequently the jaws will precede the carrier. This is effected by an arm l^6 , on an arbor 100 l^6 , fitted to turn in the guide wheel v^3 , on the principle of the sun and planet motion. This arbor carries a pinion m^6 , which engages another pinion n^6 , on the same wheel, and this latter engages a pinion o^6 , on a 105 hub p^6 , on the shaft i^2 , of the guide wheel and concentric therewith, and this hub and pinion are kept from turning by a brace q^6 , so that as the guide wheel turns, the two pinions n^6 , and m^6 make one rotation on 110 their axis while they make one revolution about the axis of the guide wheel, and in consequence of this the arm l^6 on the arbor of the pinion m^6 continues to maintain a horizontal position as it revolves about the 115 axis of the guide wheel. Now as the gripper carrier comes onto the guide wheel a wrist pin r^6 on the crank arm of the carrier is brought under the arm l^6 , of the pinion m^6 , and as this continues in a horizontal position 120 as the guide wheel rotates the arm continues above the wrist pin of the crank arm and thus forces it to precede the carrier in the lower part of its circuit around the guide wheel. The grippers are thus presented to 125 130

the paper and prepared to perform the operations before described.

Although I have described my said invention in connection with the cylinder of printing presses, I do not wish to be understood as limiting myself to such application, as it may be applied to printing presses that work without a cylinder, and in fact may be employed for feeding sheets of paper to 10 reeling machines, and delivering the same, and may be applied wherever sheets of paper are to be presented in succession to be worked or acted upon in any manner, and then piled up. Nor do I wish to be understood as 15 limiting myself to the employment of all the specified improvements in one machine as partial results may be obtained by using only a portion of them. Nor do I wish to be understood as limiting myself to the 20 special construction and arrangement of the parts herein specified, as no doubt these may be greatly modified within the range of my invention by the substitution of equivalents.

I do not wish to be understood as making 25 claim to the method of lifting sheets of paper from a pile by means of an exhaust bar or surface acting on the principle of suction, as I am aware that this was first done many years ago by M. Rimond in Europe in a 30 machine for making envelops. But

What I do claim as my invention and desire to secure by Letters Patent is—

1. The mode of operation, substantially as herein described, by which the pile or 35 piles of sheets is or are moved up or down and kept in position as the sheets are taken from or laid on the pile, that the upper sheet of the pile may at all times be in the proper position to be acted upon by the mechanism 40 which removes it or which deposits it, which mode of operation consists in lifting or depressing the table or tables on which the pile is placed by the mechanism herein described, or the equivalent thereof, in combination with the gage and holding bar, or any equivalent thereof, which rests on the top sheet to hold it down and which by its 45 position on the pile and its connection governs and controls the movements of the lifting or depressing mechanism, substantially as herein described, the said mode of operation being employed to govern the position of the pile on the feeding and receiving tables, or either, as set forth.

55 2. The mode of operation for holding the upper sheet of the pile on the receiving table on which the sheets are in succession deposited so that as the sheets are drawn over the pile in succession the sheet previously 60 deposited shall not be moved from the position in which it was deposited, the said mode of operation consisting in the use of a wing or plate which rests on the upper edge of the pile at that end of it over which the sheets 65 move as they are drawn over the pile, and

which then rises to permit the newly deposited sheet to fall, and again descends to hold it preparatory to the introduction of another sheet, the said wing or plate being operated in the manner substantially as 70 herein described or any equivalent therefor. And this I claim whether the said wing or plate be employed for the sole purpose of holding the upper sheet of the pile on the receiving table, or for this and for the purpose of 75 gaging and controlling the mechanism which depresses the receiving table.

3. Making pressure on the surface of the pile of sheets on the feeding table, and within a short distance of the edge which is 80 to be lifted, for the purpose of forcing the sheets at that end of the pile to open fan-like that the separation may be more effectively made, substantially as herein described, and this I claim whether the required pressure be made by the rounded surface on the exhaust bar, or by a separate bar having the like mode of operation.

4. Making the surface of the exhaust bar concave, substantially as herein described, 90 so that the upper sheet which is to be removed from the pile shall be drawn into the said concavity, and thereby draw its edge within the edge of the pile, the more effectively to insure the separation, as set forth. 95

5. Placing the concave surface of the exhaust bar so that it shall overlap or extend beyond the edge of the pile, substantially as described, that the whole of that portion of the sheet which is to be acted upon by the 100 exhaust may be within the concavity of the exhaust bar, thus causing the inward current to pass upward under the projecting concave surface of the exhaust bar and across the edges of the pile to insure the 105 separation of the edges of the sheets as described.

6. Blowing in a current of air at one or both ends of the concavity of the exhaust bar, substantially as herein described to insure the separation of the top sheet from the rest of the pile, preparatory to removing it from the pile, as set forth.

7. The employment of the transferring or holding bar connected with the exhaust and blowing bellows, or equivalents thereof, substantially as described, in combination with the exhaust bar, substantially as described, by means of which that end of the top sheet which has been separated from 115 the pile is transferred from the exhaust bar to, and held by, the said transfer bar until it is taken by the grippers or any equivalent therefor, that the exhaust bar may be removed preparatory to carrying off the top 120 sheet, as set forth.

8. The method of thinning the edge of the pile to insure the separation of the edges of the sheets where they are liable to adhere, by means of the rotating spring flippers, 125

substantially as described, or any equivalents therefor.

9. The mode of operation substantially as described by which the gripping end of 5 the jaws, which grip the sheet of paper, are made to maintain a fixed position, relatively to the edge of the sheet held by the transferring and holding bar, during the entire operation of gripping the sheet, and 10 during a portion of the operation of reversing the jaws by the continued motion of the endless chain or band with which the rear part of the jaws are connected, as set forth.

10. Removing the sheets in succession 15 from the pile by gripping one end of each sheet in succession with gripping jaws, after the end has been separated and lifted from the pile by other means, and rolling it off the pile by the motion of the gripping jaws 20 toward the other end of the pile substantially as specified, by which all tendency to disturb the sheets below is avoided, as set forth. I do not claim broadly the fact of rolling off the sheet from one end of the pile 25 toward the other, but limit my claim to the mode of operation specified by which I attain this end in a practical and efficient manner.

11. Making friction on both surfaces of 30 the sheet when brought over the pile on the receiving table substantially as described in combination with the grippers so that the moment it is liberated by the jaws the friction on both surfaces shall hold and leave it

in place on the pile, substantially as de- 35 scribed, whereby the accurate deposit of the successive sheets is made to depend solely on the period of opening the jaws, as set forth.

12. Making pressure on, and packing, the 40 pile of sheets on the receiving table as each sheet in succession is deposited, by means of a perforated plate substantially as specified, the perforations in the plate giving free access to air that the plate may be lifted without drawing up the sheets with it as set forth. I am aware that pressure has been made on the top sheet of a pile in the operation of depositing the sheets by means of bars called a fly, and therefore I do not 45 claim broadly making pressure on the pile, except by means of a perforated plate extending over the entire pile to pack down the entire surface, as herein specified, the small perforations preventing the sheet 50 from being lifted while they do not prevent the packing down of the pile.

13. And finally—the employment of pointed punches to punch holes in the sheets as they are piled on the receiving table, substantially as described, so that the pile may be transferred and moved without shifting the position of the sheets relatively to each other in the pile, as set forth.

ANDREW CAMPBELL.
